DESIGN.

W. W. JACKSON.
Font of Printing Type.

No. 12,138.

Patented Jan. 18, 1881.

WILLIAM W. JACKSON'S
NEW COMBINATION TYPE ORNAMENTS FOR LETTER-PRESS PRINTING.

MacKellar, Smiths & Jordan, 606-614 Sansom Street, Philadelphia.

John McPhail
WITNESSES.
Heiman Metzger

Wm. G. Jackson.

UNITED STATES PATENT OFFICE.

WILLIAM W. JACKSON, OF PHILADELPHIA, PENNSYLVANIA, ASSIGNOR TO MACKELLAR, SMITHS & JORDAN, OF SAME PLACE.

DESIGN FOR A FONT OF PRINTING-TYPE.

SPECIFICATION forming part of Design No. 12,138, dated January 18, 1881.

Application filed November 6, 1880. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to 10 which reference is made; and it consists of a design for a font of type intended for the formation of borders and ornamental surroundings for printed matter.

I will proceed to describe the various types 15 of which the font is composed.

The motive of the design is Eastern.

Nos. 1, 29, and 46 are representations of vases.

Nos. 2 and 3 are representations of flowers. 20 No. 4 is a representation of the trunk of a tree.

No. 5 is a quadrant, shaded near its lower part upon the face by a series of inclined lines, and at the upper and lower points of its 25 arc and about centrally by the heavy triangular figures, as shown.

No. 6 is a line placed above a parallelogram divided into four right-angled triangles, two of which are shaded by a series of light vertical 30 lines, a section of No. 51.

No. 7 is the representation of a dog.

No. 8 is a section of No. 51.

No. 9 is two parallel lines, between which are placed the unshaded oblong figures with 35 curved termination at one end.

Nos. 10 and 12 are a combination of heavy and light lines; may be employed to represent the sky or water.

No. 11 is a representation of a lizard.

40 No. 13 is a representation of a bell.

Nos. 14 and 15 represent characters or symbols of the Japanese language.

No. 16 is an ornament for the upper or top of a banner-pole.

45 No. 17 is a shaded prismatic figure.

Nos. 18 and 19 represent sections of braided or woven work.

No. 20 is a section of a Japanese mirror.

No. 21 is a section of a fret.

50 Nos. 22, 23, 32, 50, 61, 65, 66, and 120 are figures illustrative of Japanese life.

Nos. 24, 25, 26, 27, and 28 are sections of braided straw-work.

No. 30 is a representation of a Japanese lamp-post.

Nos. 31 and 38 represent Japanese robes or garments.

No. 33 is a figure taken from a Japanese or Chinese picture.

Nos. 34 and 45 are representations of Japanese boats, the latter a sail-boat.

Nos. 35, 36, and 37 are sections of a Japanese vessel.

Nos. 39, 40, and 41 are sections of a border ornamented upon its face about centrally by 65 the flowers inclosed within the shaded oblong square.

No. 42 is a quadrant, shaded upon the face, at its lower left-hand corner, by a series of light horizontal lines rising above each other. 70 Upon the right of these is placed a heavy curved line, from which extend upward at intervals to the upper part of the figure the three vertical lines, the figure surmounted about centrally by the Anthemion-like figure, upon each side 75 of which is placed a triangular-shaped figure.

No. 43 and 44 represent Japanese dragons.

No. 47 is a representation of a Japanese shrub.

No. 48 is a representation of a fret.

No. 49 is a representation of a Japanese banner.

No. 51 is a figure formed by combining a series of the sections shown in Nos. 6, 8, and 21. The upper part has already been described, 85 and is a series of parallelograms divided into four right-angled triangles, two of which are shaded by a series of light vertical lines, followed by a series of fan-shaped figures placed below, and below them frets, as shown in No. 21. 90

Nos. 52 and 53 are sections of a border composed of a heavy horizontal line succeeded by a group of shaded petal-like figures placed below, and this group followed by a second figure of like character below the groups of petals, so 95 arranged that one group shall be found upon the right of the figure and the other group upon the left.

No. 54 is a group composed of a series of shaded petaloids arranged in a fan shape, 100 bounded on the left and above by the heavy lines.

No. 55 is the same, the lines on the left and top omitted.

Nos. 56 and 57 are figures formed by dividing No. 55 into two sections of equal size.

5 Nos. 58 and 59 are figures formed by dividing No. 54 into two sections of equal size.

No. 60 is a representation of a peacock.

Nos. 62 and 63 are representations of box-covers, one formed of interwoven straw, and 10 the other, No. 63, ornamented by the interwoven straw and by the stem bearing leaves, as shown.

15 No. 64 is a cornucopia-like figure, ornamented upon its face by the cruciform figure, below which are placed the inclined lines, meeting each other at a point, followed by a shaded triangular figure, below which is placed a fret-like ornament.

Nos. 67 and 68 are sections of frets.

20 No. 69 may be designated as an irregular fret adorned by sections of interwoven work.

No. 70 is the base of the figure, a curved line, over which is placed, about centrally, an Anthemion-like figure, over which is placed, about 25 centrally, a heavy triangular figure, and upon each side a series of light curved lines following each other.

No. 71 is a quadrantal figure, surmounted, about centrally, by a triangular ornament, and 30 ornamented upon its face by the heavy wedge-shaped figure, from the divided part of which project, on each side, the heavy inclined lines, as shown.

No. 72 is a quadrantal figure, shaded upon 35 its face by a series of light curved lines, and ornamented, about centrally, by a heavy conical figure, as shown.

Nos. 73, 74, and 75 may be designated as symbols of the Corea.

40 No. 76 shows two flowers of the star grass, placed one a short distance above the other, and connected by a line passing through them. Above and below the line are placed the unshaded dots.

45 No. 77 is a Japanese bauner crossed by a bamboo pole.

No. 78 is a section of knotted work placed above a second section of knotted work, the upper one shaded by a series of light lines 50 placed below it.

No. 79 is a center ornament for a border, consisting of a crown-like ornament, from which rises about centrally a lily resting upon a heavy groundwork shaded upon each side by a series of light lines.

No. 80 is a representation of one of the grasses of Japan.

No. 81 is a triangular figure shaded upon one side of its face by the heavy lines and 60 upon the other side by the light lines, above which are placed the two triangular figures, one shaded on its face by the heavy lines, the other by the light lines, the latter so placed that the light-line-faced triangle is placed 65 above the heavy-line-faced triangle of the lower figure, and the heavy-line-faced triangle is above the light-line-faced triangle of the lower figure.

No. 82 is a square divided into three right-angled triangles, the lower one ornamented 70 about centrally by an unshaded dot. One of the upper ones is shaded by a series of light horizontal lines, the other by heavy vertical ones.

No. 83 is the outer boundary of the figure, 75 a horizontal line, from which extends a vertical line upon the right. The inner figure is a square, in the upper right-hand corner of which is a small heavy square, and in the lower right hand corner a heavy triangular figure. 80 In the upper left-hand corner is a heavy triangular figure, and the space between the heavy square in upper right-hand corner and the left-hand boundary of the main square is shaded by a series of light parallel lines. 85

No. 84 is a semicircular figure ornamented upon its face by the flower-like ornament and a series of light and heavy horizontal lines. Upon the right is placed the heavy pointed ornament; upon the left a pointed ornament shaded upon its face by a series of light inclined lines.

No. 85 is a cornucopia-like ornament ornamented upon its face by the interwoven-like ornament.

No. 86 is a triangular figure ornamented upon its face by a series of light horizontal lines and the heavy triangular figures. 95

No. 87 is a figure the lower portion of which is a trapezium surmounted by two right-angled triangles, the upper portion of the trapezium shaded by a smaller trapezium, which is shaded on its face by a still smaller trapezium and a series of light lines. The triangles are partially shaded by a series of light lines. 100 105

No. 88 is a quadrantal figure surmounted about centrally by the cone-shaped figure, the lower portion of the figure ornamented by the pistil-like ornaments, the upper portion of the figure above the heavy curved line ornamented 110 by the short light lines and the flower-like ornaments, above which rises about centrally the grass-like ornament.

No. 89 is the lower portion of the figure, a crown-like ornament upon a shaded groundwork of light curved lines; above this a heavy curved line surmounted centrally by a spear-head-like ornament adorned upon its face by a flower-like ornament. 115

No. 90 is a quadrantal figure ornamented at 120 its base by the lace-work, above which is a heavy curved line. Above this are placed a series of triangular figures shaded upon their faces by a series of light lines. Above these are placed a heavy curved line followed by a 125 light curved line, these surmounted by a shaded conical figure, in the center of which is placed a flower-like ornament, and upon the sides of which are placed the curved lines.

Nos. 91 to 98 are representations of tiles. 130

No. 99 is an imitation of the design upon a box-cover composed of interwoven straw-work.

The prominent ornament of the figure consists of a heavy circle upon the left, in the center of which is placed a light dot surrounded by a heavy circle, from which proceed a series of 5 light-rays extending to the outer circle, the spaces between which are shaded by the heavy pointed figures, as shown.

Nos. 100 and 103 represent Japanese or Chinese mats.

10 No. 101 may be defined as a groundwork in imitation of a woven pattern, in lower left-hand corner of which is placed a shaded ring, forming, as it were, a continuation of this pattern, within which ring is placed a heavy shaded ring, and above and to the right of which is placed a heavy fret, above which is 15 the unshaded fret.

No. 102 is an idealized group of ferns and grasses.

20 No. 104 is an imitation of interwoven straw-work, the leading ornamentation of which consists of the three circular figures, one ornamented by an interior ring composed of short lines, another by an interior ring composed of 25 small dots, and the third by an inner ring formed of knotted cord.

No. 105 is a fret adorned upon its face by the looped figures, as shown. Upon the left of this is placed the curved figure, ornamented 30 upon its face by the pistil-like ornaments upon the light groundwork.

No. 106 is an ornament in imitation of a woven fabric.

No. 107 is a Japanese beetle.

No. 108 represents worms or caterpillars. 35

No. 109 is a representation of a lily.

Nos. 110 and 112 are representations of butterflies.

No. 111 is a crane.

Nos. 113 and 114 are grasses.

Nos. 115, 116, 117, 118, and 119 are leaves 40 of the bamboo.

No. 121 is an idealized group of ferns and grasses.

No. 122 is a representation of a web supported by leaves. 45

Nos. 123, 124, 125, and 126 are sections of bamboo.

Nos. 127 and 128 are representations, one of a bird mounted on a bamboo reed, the other 50 of a serpent intertwined around a stalk of the same.

Nos. 129 and 130 are stalks of bamboo.

Having now set forth my invention, what I claim as new is—

The design for a font of printing-type, as 55 shown and described.

WM. W. JACKSON.

In presence of—

W. V. H. HICKS,

A. SIDNEY DOANE.